2 SHEETS—SHEET 2.

UNITED STATES PATENT OFFICE.

JOHN A. MCINTIRE, OF ASHEVILLE, NORTH CAROLINA.

SHAVING APPLIANCE.

1,183,747.

Specification of Letters Patent. Patented May 16, 1916.

Application filed July 8, 1915. Serial No. 37,867.

To all whom it may concern:

Be it known that I, JOHN A. MCINTIRE, a citizen of the United States, residing at Asheville, in the county of Buncombe and State of North Carolina, have invented certain new and useful Improvements in Shaving Appliances; and I do hereby declare the following to be a full, clear, and exact description of the invention, such as will enable others skilled in the art to which it appertains to make and use the same.

This invention relates to a device particularly designed for facilitating the operation of shaving by oneself, and the primary object of the invention is to provide a device which includes a yoke for resting upon the shaver's shoulders, which yoke supports a platform and a framework which latter framework pivotally supports a mirror forwardly of the operator's face, so as to enable him to support the mirror where he can get the best light upon his face for shaving.

Another object of this invention is to provide means for detachably supporting various appliances used in shaving, such as a shaving mug, soap, and razor, and further to provide a device which may be taken down and folded into a compact form when not in use.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:

Figure 1 is a side elevation of the improved shaving appliance, showing the same supported for use, Fig. 2 is a cross section through the appliance, showing the mirror supporting brackets and mirror, Fig. 3 is a plan view of the device, Fig. 4 is a sectional view on the line 4-4 of Fig. 3, and Fig. 5 is a sectional view on the line 5-5 of Fig. 3.

Referring more particularly to the drawings, 1 designates the yoke of the improved shaving appliance, which is constructed of a strand of wire bent substantially U-shaped, for extending across the shoulders of an operator, and downwardly along the chest, as is shown in Fig. 1 of the drawings.

The lower ends of the legs of the yoke 1 are bent angularly to the yoke, as is shown at 2, and they are slidably mounted in rolls 3 and 4, which are formed along the side edges of the platform 5. The platform 5 is constructed of sheet metal, or any analogous material, and it has spring or resilient arms 6 and 7, which are substantially U-shaped secured thereto. The bight portions of the bars 6 and 7 rest upon the upper surface of the platform 5, and are secured to the platform, substantially equidistant of their ends by means of rivets or analogous fastening means indicated at 8. The upstanding legs of the members 6 and 7 are slightly curved as is clearly shown at 9, so as to provide inwardly bulging portions for engagement with a shaving mug or like device, indicated at 10. A pair of U-shaped members 11 and 12, which are also constructed of resilient material, are secured to the platform 5, to one side of the members 6 and 7. The U-shaped members 11 and 12 are smaller than the members 6 and 7, and are constructed in duplicates thereof, being provided for engaging and supporting a box of shaving powder, a shaving stick or the like, as is indicated at 13. Positioned rearward of, and intermediate the members 6 and 7 and 11 and 12, is a resilient or spring strap 14, which has one end secured to the upper surface of the platform 5 by means of a rivet or analogous fastening device 15. The strap 14 is curved downwardly, a short distance inwardly from its outer end, as shown at 16, and it is provided for engaging and holding a razor in engagement with the upper surface of the platform 5, as indicated at 17.

A mirror supporting bracket 20 is provided, which includes legs 21 and 22, which have their lower ends bent angularly to the body of the legs and adapted, as at 23, for insertion into the rolls 3 and 4, which are formed on the edges of the platform 5, oppositely from the angled ends 2 of the legs of the yoke 1. The legs 21 and 22 are braced intermediate their ends by crossing brace rods 24. The upper ends of the legs 21 and 22 are bent substantially at right angles to the bodies of the legs, and inwardly toward each other, as is shown at 26. The inwardly bent ends 26 pivotally support a mirror 27, which may be constructed in any desired manner. The legs 21 and 22 are of sufficient length for positioning the mirror for

wardly of the face of the operator, so that the mirror may be positioned properly for facilitating the operation of shaving by the person using the device.

5. When the device is not in use, the bracket 20 and the yoke 1, may be disconnected from the platform 5, and laid downwardly upon the platform, or positioined in any desired way for causing the shaving appliance to 10 assume a compact form for storage.

From the foregoing description taken in connection with the accompanying drawings the advantages of construction and of the method of operation of the improved 15 shaving appliance will be readily apparent to those skilled in the art to which this invention appertains and, while in the foregoing description, the principle of the operation of this invention has been described 20 together with various features of construction, it is to be understood that certain minor features of construction, combination and arrangement of parts may be altered to suit practical conditions provided such 25 alterations are comprehended within the scope of what is claimed.

What is claimed is:—

1. In a device as set forth, a yoke formed of a strand of wire bent substantially U-shaped for extending about an operator's neck and downwardly over his chest, the lower ends of the legs of said yoke being bent angularly to the legs, a platform having its edges rolled, said angled ends adapted 35 for removable seating in said rolls, and a bracket adapted to support a mirror removably carried by said platform remote from said yoke.

2. In a device as set forth, a yoke formed 40 of a strand of wire bent substantially U-shaped for extending about an operator's neck and downwardly over his chest, the lower ends of the legs of said yoke being bent angularly to the legs, a platform having 45 its edges rolled, said angled ends adapted for removable seating in said rolls, a bracket adapted to support a mirror remov-

ably carried by said platform remote from said yoke, a plurality of substantially U-shaped resilient arms secured to the upper 50 surface of said platform and arranged for forming article receiving and retaining sockets.

3. In a device as set forth, a yoke formed of a strand of wire bent substantially U-shaped for extending about an operator's neck and downwardly over his chest, the lower ends of the legs of said yoke being bent angularly to the legs, a platform having its edges rolled, said angled ends adapted 60 for removable seating in said rolls, a bracket adapted to support a mirror removably carried by said platform remote from said yoke, a plurality of substantially U-shaped resilient arms secured to the upper 65 surface of said platform and arranged for forming article receiving and retaining sockets, a resilient strap having one end secured to said platform, said strap being curved adjacent to its outer end for engaging and holding a razor in engagement with 70 said platform.

4. In a device as set forth, a platform constructed of sheet metal having its opposite side edges rolled, a pair of upstanding 75 legs, the lower ends of said legs being bent angularly to the upstanding portions of the legs for removable seating in the rolled edges of said platform, the upper ends of said legs being bent inwardly toward each other, 80 the inwardly bent upper ends of said legs adapted to pivotally support a mirror, brace rods connected to and extending from one of said legs to the other, and means detachably connected to said platform remote from said 85 mirror supporting bracket for suspending the platform and mirror bracket from an operator's body.

In testimony whereof I affix my signature in presence of two witnesses.

JOHN A. McINTIRE.
